(57) **CLAIM**

We claim the ornamental design for a strip track light, as shown and described.

DESCRIPTION

FIG. 1 is a perspective view of a strip track light in state of use showing our new design;

FIG. 2 is a front view thereof;

FIG. 3 is an enlarged view of the selected portion 3 in FIG. 2 thereof;

FIG. 4 is a perspective view of the strip track light viewed from the left and rear;

FIG. 5 is an enlarged view of the selected portion 5 in FIG. 4 thereof;

FIG. 6 is a perspective view of the strip track light viewed from the left and front;

FIG. 7 is an enlarged view of the selected portion 7 in FIG. 6 thereof;

FIG. 8 is a rear view thereof;

FIG. 9 is a top view thereof;

FIG. 10 is a bottom view thereof;

FIG. 11 is a right side view thereof; and,

FIG. 12 is a left side view thereof.

The dashed broken lines depict environmental structure which form no part of the claimed design.

The dot-dash broken lines in FIGS. 2, 4, and 6 are for the purpose of illustrating the boundaries of the enlarged sections, shown respectively in FIGS. 3, 5, and 7, and form no part of the claimed design.
